UNITED STATES PATENT OFFICE.

CASPER M. B. BOOS, OF MUSCATINE, IOWA.

CROWN AND BRIDGE WORK.

No. 884,977.

Specification of Letters Patent. Patented April 14, 1908.

Application filed October 17, 1904. Serial No. 228,697.

To all whom it may concern:

Be it known that I, CASPER M. B. Boos, D. D. S., a citizen of the United States, residing at Muscatine, in the county of Muscatine and State of Iowa, have invented a certain new and useful Crown and Bridge Work, of which the following is a specification.

The objects of my invention are to provide a simple, durable and inexpensive crown for 10 teeth in which the porcelain forming the body of the tooth can be readily and easily attached to the backing without heating; that is, the backing is first molded into a desirable shape and the porcelain is then placed there- 15 in and maintained by means of pins extending through slots in the backing and engaging surface thereof which is away from the porcelain, the body portion of these pins being first embedded in the porcelain.

20 A further object is to provide a backing for teeth which will not have to be removed if the porcelain should at any time be severed from the backing, owing to the particular construction and arrangement of this backing. By the use of my backing the necessity 25 of removing the cap and pin which secure the backing to the teeth remains intact even though the porcelain body portion of the tooth is broken from the backing, so that by 30 simply replacing the porcelain which has been broken away, the teeth are repaired, which process saves the root of the tooth affected materially.

35 My invention consists in certain details in the construction, arrangement and combination of the various parts of the device, whereby the objects contemplated are attained, as hereinafter more fully set forth, pointed out in my claims and illustrated in 40 the accompanying drawings, in which—

Figure 1 is a perspective view of a complete tooth after my crown and backing has been placed upon the root. Fig. 2 is a sectional view of the same. Fig. 3 is a sectional view of the root of the tooth prepared for 45 fixing my crown to it. Fig. 4 is a detail, sectional view of the capping with the pin for holding it in place held to the tooth and my backing attached to it as it appears when 50 whole. Fig. 5 is a detail, sectional view of the backing before it has been attached to the capping. Fig. 6 is a sectional view of the backing with the pin protector attached to it first before the backing has been shaped 55 to be attached to the capping. Fig. 7 is a detail view of the body portion of the tooth

which is attached to the backing showing the pins for connecting the tooth to the backing. Fig. 8 is a plan view of the backing before it has been shaped to be attached 60 to the capping, and Fig. 9 is a detail view of the protector for the pins.

Referring to the accompanying drawings, I have used the reference numeral 10 to indicate the root of an upper tooth in which the 65 crowning is cut off at its lower portion slightly above the lower portion of the gum. After the tooth has been cut off an opening 11 is bored into it which is designed to receive a pin, hereinafter described. A cap- 70 ping 12, having the pin 13 extending upwardly from its central portion, is provided, which is of the ordinary construction, except that it has an extension to which the porcelain tooth is to be secured. Firmly at- 75 tached to the lower inner portion of the cap- ping is a backing 14 having two slots 15 ex- tending through it which are designed to re- 80 ceive the pins which are attached to the body portion of the tooth as more fully described 85 hereinafter. Attached to the inner rear sur- face of the backing 14 is a pin protector 16 having two depressions 17 therein which are immediately behind the slots 15, so that the 90 heads of pins which are placed in the slots 15 will be received in the depressions 17, and said protector will protect the heads of these pins when these heads are in the protector. Gold or other metal is then flowed around the 95 rear of the backing and of the pin protector 100 so as to make a perfectly smooth surface on the interior of the backing.

It will be clearly seen that on account of the way in which the protector 16 is attached to the backing 14, there will be recesses 18 in 95 which the pin heads will rest and these heads will also engage the inner rear surface of the backing 14 and be maintained securely relative thereto. When the capping and back- 100 ing have been thus formed and secured relative to each other, a soldering material is placed in the opening 11 and around the in- 105 terior of the capping and the pin 13 is in- serted in the opening 11 and the capping is slipped over the exterior of the root 10 until the portion 19 of the capping rests against the outer portion of the tooth. Thus the capping is securely held in position relative to the roots and maintained in this position.

110 The body portion 20 which is made of porcelain or other desirable material is shaped to be placed against the backing 14 and the

two pins 21 are inserted into the body portion 20 from the back thereof, and the outer portions 22 of said pins are bent upwardly so that they can be inserted in the openings 5 15 and moved upwardly a slight distance and enter the recesses 18 when the body portion 20 is in the proper position relative to the backing 14 and the capping 12. When the pins are in this position and the body portion 10 20 has been thus shaped, soldering material is placed on the inner surface of the body 20 and around the heads of the pins 21. Then the heads 22 of these pins are inserted through the slots 15 and the pins are moved 15 upwardly so that the body engages the capping and a perfect crown is formed.

I claim

1. A tooth crown, comprising a backing having slots therein, a body, pins in the body 20 extending through the slots and engaging the rear surface of the backing, and a pin guard firmly attached to the backing, having two depressions therein immediately at the rear of the slots in the backing.

2. A capping having a pin extending outwardly from its central portion and substantially parallel with its sides, a backing designed to be securely fixed to the root of a tooth, a backing integral with the capping having slots extending through it, a pin guard secured to the backing over the pins, having depressions therein immediately at the rear of the slots in the backing, a body portion having pins extending rearwardly from it, an angular head thereon designed to pass through said slots and rest in the depressions between the protector and the backing.

3. A tooth crown, comprising a backing and slots therein, a body, pins in the body extending through the slots, an extension of the pin designed to engage the rear surface of the backing, and a pin guard attached to the rear surface of the backing.
